GOLF YARDAGE REGISTERING DEVICE

Lacy L. King, Tulsa, Okla.

Application December 4, 1941, Serial No. 421,653

3 Claims. (Cl. 265—21)

This invention relates to a device for registering or indicating the approximate distance a golf ball would have traveled if the flight of said ball were not arrested by the device.

Briefly described, the present invention relates to that type of device in which a yieldable target is provided against which the golf ball may be driven, said target being so arranged that the impact of the ball driven against the same will operate a distance indicating means.

The primary object of the present invention is the provision of a device of the above kind which is simple in construction, economical to manufacture, and highly efficient in use.

Other objects and features of the present invention will become apparent from the following description when considered in connection with the accompanying drawings, and the invention consists in the novel form, combination and arrangement of parts hereinafter more fully described, shown in said drawings and claimed.

In the drawings:

Figure 1 is a side elevational view of a golf yardage indicating device constructed in accordance with the present invention.

Figure 2 is a top plan view thereof.

Figure 3 is a front elevational view of the same.

Figure 4 is an enlarged fragmentary view partly in top plan and partly in section, showing the preferred manner of mounting the target for horizontal movement.

Figure 5 is a fragmentary section on line 5—5 of Figure 4.

Figure 6 is an enlarged plan view showing details of the indicating means.

Figure 7 is a horizontal section on line 7—7 of Figure 9.

Figure 8 is a view similar to Figure 7 with the parts in a shifted position.

Figure 9 is a fragmentary vertical section on line 9—9 of Figure 6.

Figure 10 is a wiring diagram showing the manner of wiring the parts of Figure 6 to the indicating lights.

Figure 11 is a view similar to Figure 10, with parts omitted, illustrating the parts in a different position, and

Figure 12 is a view similar to Figure 11 with the parts in a still further position.

Referring in detail to the drawings, the present device includes a ball-receiving funnel which may consist of a suitable frame 5 having the sides and top covered with sheets of canvas 6. The ball-receiving funnel is open at the back or

smaller end, and disposed directly behind this open end of the funnel is a target consisting of a vertical frame 7 having a sheet of canvas stretched thereover, the frame 7 being disposed at the front of a horizontally movable carrier frame 9 mounted for free movement in a base frame 10 and normally yielding urged forwardly by a spring 11. As shown in Figures 4 and 5, ball or antifriction bearings 12 are provided between the sides of the carrier frame 9 and the base frame 10 so as to promote the ease of movement of the target. Disposed upon the floor or ground in front of the funnel 5, 6 is a ball-catching mat consisting of a strip of canvas 13 laid across transversely arranged spaced cleats or rails 14 disposed upon the ground or floor. At the forward end of this mat is arranged a suitable platform 15 having a means for tee-ing a golf ball 16 thereon in position to be struck and driven into the funnel so as to strike the target. By arranging the strip of canvas 13 across the cleats or bars 14, the strip of canvas is provided with valleys or depressions transversely of the mat which will aid in catching or arresting the travel of the golf ball after it rebounds from the target forwardly out of the funnel.

Registering or indicating means is associated with the target 7 for showing the approximate distance, in yards, that the golf ball would have traveled if the flight of said ball were not arrested by the target of the present device. This means consists of certain elements arranged upon a base plate 17 of a casing 18 (see Figs. 6 and 2), and controlling the lighting of yardage indicating lights 19 (Fig. 10) arranged within the respective compartments of an indicating lamp 20 preferably mounted at the top of the funnel 5, 6. As shown, the light controlling means includes a contact lever 21 pivoted intermediate its ends as at 22 upon the base plate 17, and having its outer end arranged to successfully engage an arcuate series of contacts 23 connected by wires 24 to one contact of each of the respective indicating lights 19. The contact lever 21 is in turn connected by wire 25 with one side of a source of electricity, and a tension spring 26 normally yieldingly swings the lever 21 to the initial position of Figure 6 to one side of the series of contacts 23. The casing 17, 18 is arranged and set in place within the carrier frame 9 upon a suitable support, and behind the target 7, 8. Extending forwardly from the casing 17, 18 is a plunger 27 whose forward end is connected to the target so as to be movable therewith, the rear portion of plunger 27 being slid-

ably guided in a block 28 mounted upon the base plate 17. The rear portion of plunger 27 has an upstanding rib provided with a rearwardly directed arm 29 having spaced depending lugs 30 between which is slidably guided a horizontal slide 31 of insulating material. Normally engaged spring contacts 32 and 33 are carried by said rib and extend rearwardly beneath the arm 29 in position to have the forward end of insulating slide 31 pass between the ends thereof when said slide 31 is urged forwardly. Contact 33 has an extension 34 projecting forwardly and arranged to slidably engage a further contact 35 fixed upon the guide block 28. Rearward movement of slide 31 is limited by a transverse pin 36 engageable with one of the guide lugs 30, and this pin 36 is also arranged in the path of a pin 37 projecting upwardly from the guide block 28. The arrangement is such that when the plunger 27 is forced rearwardly, the slide 31 will engage a pin 38 rising from the contact lever 21, thereby forcing the slide 31 forwardly between the contacts 32 and 33 as shown in Figure 11. Also, when the plunger 27 moves forwardly so that the slide 31 disengages from pin 38, the pin 36 will engage pin 37 and cause rearward shifting of slide 31 from between the ends of contacts 32 and 33 as shown in Figure 12. In the normal forward position of plunger 27, the engaging end of contact 34 is disposed forwardly of contact 35 and out of engagement with the latter as shown in Figure 10.

Contact 32 is connected by a wire 38a with one side of the source of electricity or that side opposite which the wire 25 connects and to which the remaining sides of lamps 19 are connected by means of a wire 39. The second named side of the source of current is connected by wire 40 to one side of a solenoid coil 41 whose other side is connected by wire 42 with the contact 35. A plunger 43 of the solenoid coil 41 is connected by a link 44 with the free end of a ratchet segment 45 pivoted at its other end as at 46 to the base plate 17 and having ratchet teeth 47 on its inner edge arranged to be successively engaged by the adjacent shorter end of contact lever 21. The core or plunger 43 of the solenoid coil 41 is normally yieldingly projected so as to swing the segment 45 toward the adjacent end of contact lever 21.

In operation, the parts will be set normally as shown in Figures 6 and 10, the slide 31 being disengaged from between the contacts 32 and 33, the contact 34 being disengaged from contact 35, and pin 38 of contact lever 21 being engaged with the adjacent end of slide 31 carried by plunger rod 27. When the golf ball 16 is driven into the funnel and against the target, the impact of the ball against said target causes rearward movement of the latter and corresponding rearward movement of plunger rod 27. As pin 36 leaves pin 37, slide 31 is forced forwardly between the contacts 32 and 33 as shown in Figure 11, thereby breaking the circuit of the solenoid coil 41 so that the latter will not be operated even though the contact 34 engages contact 35 during the rearward movement of plunger rod 27. During this rearward movement of plunger rod 27, the contact lever 21 is swung to the left for a distance corresponding to the impact against the target, and when rearward movement of plunger 27 ceases and forward swinging movement of contact lever 21 also ceases, said contact lever 21 will be maintained in its furthest swung position by engagement of the ratchet seg-

ment 45 therewith. The light in circuit with the contact finally engaged by the lever 21 will remain lighted and will give an indication as to the approximate distance the golf ball would have traveled if the flight of said ball had not been arrested by the target. This distance can be denoted in yards on the lens of the light compartment, the successive lights being suitably graduated in yards. As soon as the ball leaves the target, the latter will return to its forward normal position as shown in Figure 12, leaving the contact lever 21 in its shifted position and finally causing movement of the slide 31 from between the contacts 32 and 33 by engagement of pin 36 with pin 37 as shown in said Figure 12. When another ball is driven against the target, the rearward movement of plunger rod 27 will cause engagement of contact 34 with contact 35 before the contacts 32 and 33 are separated by forward movement of slide 31 to its engagement with contact lever 21. Thus, solenoid coil 41 will be momentarily energized so as to retract its core or plunger 43 and momentarily release the ratchet segment 45 from said contact lever 21 so that the latter will be automatically returned toward normal position by spring 26, if the plunger 27 is not driven rearwardly sufficiently far to cause further forward swinging of said lever 21, but is only driven rearwardly a lesser distance than previously driven. Thus, a proper yardage indication will be had under the circumstances and particularly if the travel indication is less than a previous travel indication in which the contact lever 21 has been left. As soon as contact lever 21 engages slide 31 and forces it forwardly, the contacts 32 and 33 will be separated to break the circuit of the solenoid coil 41 and permit the segment 45 to promptly engage the adjacent end of the lever 21 again.

From the foregoing description, it is believed that the construction and operation, as well as the advantages of the present invention will be readily appreciated and understood by those skilled in the art. Minor changes are contemplated in the details of construction illustrated and described, such as fairly fall within the spirit and scope of the invention as claimed.

What I claim as new is:

1. A golf yardage registering device comprising a funnel adapted to guide a golf ball, a rearwardly yieldable target arranged at the rear of said funnel for arresting the flight of said golf ball, and means operative in conjunction with said target for indicating the distance of an uninterrupted flight of the golf ball, means yieldingly urging said target forwardly toward the funnel, said indicating means including a plunger attached to and extending rearwardly from the target, a contact lever operable by said plunger, a plurality of contact points in operable relation with said contact lever for completing electric circuits when said contact lever is swung by said plunger, a ratchet segment yieldingly engaging said contact lever to releasably retain the same in any position to which it is swung by said plunger, a solenoid connected to said ratchet segment and operable for releasing the latter from said contact lever, and switch means operable upon rearward movement of said plunger for closing the circuit of said solenoid to release said ratchet segment.
2. A golf yardage registering device comprising a funnel adapted to guide a golf ball, a rearwardly yieldable target arranged at the rear of said funnel for arresting the flight of said golf

ball, and means operative in conjunction with said target for indicating the distance of an uninterrupted flight of the golf ball, means yieldingly urging said target forwardly toward the funnel, said indicating means including a plunger attached to and extending rearwardly from the target, a contact lever operable by said plunger, a plurality of contact points in operable relation with said contact lever for completing electric circuits when said contact lever is swung by said plunger, a ratchet segment yieldingly engaging said contact lever to releasably retain the same in any position to which it is swung by said plunger, a solenoid connected to said ratchet segment and operable for releasing the latter from said contact lever, switch means operable upon rearward movement of said plunger for closing the circuit of said solenoid to release said ratchet segment, and further switch means operable upon continued rearward movement of said plunger for breaking the circuit of said solenoid and permitting retention of the contact lever in the position to which it is fully swung by means of said ratchet segment.

3. A golf yardage registering device comprising a funnel adapted to guide a golf ball, a rearwardly yieldable target arranged at the rear of said funnel for arresting the flight of said golf ball, and means operative in conjunction with said target for indicating the distance of an uninterrupted flight of the golf ball, means yield-

ingly urging said target forwardly toward the funnel, said indicating means including a plunger attached to and extending rearwardly from the target, a contact lever operable by said plunger, a plurality of contact points in operable relation with said contact lever for completing electric circuits when said contact lever is swung by said plunger, a ratchet segment yieldingly engaging said contact lever to releasably retain the same in any position to which it is swung by said plunger, a solenoid connected to said ratchet segment and operable for releasing the latter from said contact lever, switch means operable upon rearward movement of said plunger for closing the circuit of said solenoid to release said ratchet segment, further switch means operable upon continued rearward movement of said plunger for breaking the circuit of said solenoid and permitting retention of the contact lever in the position to which it is fully swung by means of said ratchet segment, said last named switch means comprising normally engaged contacts, a slide arranged in the path of and operable by the contact lever for separating said normally engaged contacts upon rearward movement of the plunger, and stop means to limit movement of said slide by said contact lever to permit engagement of said normally engaged contacts with each other upon return of the plunger to its forward position.
